CONCRETE REINFORCING BAR SUPPORT

Clarence H. Scarborough, Jr., Grand Prairie, Tex., assignor to Frank Holister Co., Inc., a corporation of California

Filed Feb. 27, 1964, Ser. No. 78,802

Term of patent 14 years

(Cl. D51—1)

FIG. 1 is a perspective view of a concrete reinforcing bar support embodying my new design,

FIG. 2 is a side elevational view,

FIG. 3 is a front end elevational view,

FIG. 4 is a rear end elevational view,

FIG. 5 is a top plan view, and

FIG. 6 is a bottom plan view.

I claim:

The ornamental design for a concrete reinforcing bar support, as shown.
